EXTENDED BEARING MOTOR

Hermann S. Bogaty, Philadelphia, Pa., assignor
to Proctor & Schwartz, Incorporated, Philadelphia, Pa., a corporation of Pennsylvania

Application October 22, 1937, Serial No. 170,443

9 Claims. (Cl. 172—36)

This invention relates to driving units of the type disclosed in the mutual assignee's prior patent to A. O. Hurxthal, No. 2,050,180, dated August 4, 1936 and the reissue thereof No. 20,285 bearing date of March 9, 1937.

The object of the present invention is to create a circulation of cooling air completely around the extended bearing of the driving unit disclosed in said patents i. e. the bearing disposed at that end of the unit which normally projects into the heated atmosphere within the casing of the drier to which the driving unit is applied for rotating an impeller by which heated atmosphere etc., within the drying casing is maintained in circulation.

In the accompanying drawings:

Fig. 1 is a longitudinal elevation of the driving unit, with an air impeller mounted on one end of the drive shaft and located within a drying chamber, one wall of which is shown in section with the driving unit projecting therethrough;

Fig. 2 is a longitudinal sectional elevation of the unit shown in Fig. 1;

Fig. 3 is a transverse sectional elevation taken on the line 3—3, Fig. 2;

Fig. 4 is a sectional elevation taken on the line 4—4, Fig. 2 and illustrating the section line 2—2 on which the sectional elevation of Fig. 2 is taken;

Fig. 5 is a transverse sectional elevation similar to Fig. 4 but illustrating a modification of the invention; and

Fig. 6 is a sectional elevation taken on the line 6—6, Fig. 5.

Fig. 1 illustrates the driving unit as being applied to suitable drier or processing apparatus, generally indicated at 1. The drier etc. comprises suitable top and side walls 2, which form a substantially closed chamber 3. Within the chamber 3 is a fan, blower, or other driven element 10 which is intended to be rotated by the power unit forming the subject of the present invention.

The driven element 10 is secured to one end of a drive shaft 11. The shaft 11 projects through the chamber wall 2. The shaft 11, for the same reasons as noted in the prior patents referred to, is in one piece and is rotatably mounted in bearings 12 and 13 which are disposed at the opposite ends respectively of a rigid, hollow structure 15.

The rigid hollow structure 15 is provided with a transversely extending flange or a series of radially extending lugs 16, which, in either case is disposed in a plane intermediate the opposite ends of the structure 15. The flange 16 is

adapted to be secured to the wall 2 by any suitable means, such, for example, as bolts 17.

The hollow structure 15 is secured to the wall 2 with one end 15a of said structure projecting through an opening 18 formed in the wall 2 and the opposite end portion 15c and the main intermediate portion 15b of the structure 15 disposed outside the chamber 3, beyond the wall 2 thereof.

In the present instance the bearing 12 and the supporting flange or series of lugs 16 are carried by the long bonnet end 15a of the hollow structure 15 and the bearing 13 is carried by the short bonnet end 15c of said structure.

The intermediate or main body portion 15b of the hollow structure 15 forms a housing for an electric motor. The stator 20 of said electric motor is secured in the portion 15b of the structure 15 and the rotor 21 of said motor is secured directly to the drive shaft 11, adjacent the short end bonnet 15c of the structure 15.

The long bonnet end 15a of the structure 15 is elongated to project into the chamber 3, to any desired extent, depending upon the position of the driven element 10 with respect to the wall 2, in order that the shaft 11 will be supported by the bearing 12 relatively close to the driven element 10, to prevent the element 10 from, of necessity, being otherwise mounted on a long overhanging and unsupported end of the drive shaft 11.

The bearing 13, as clearly shown in Fig. 2, is disposed immediately adjacent the rotor 21, in order to provide the necessary support for said rotor during high speed rotation thereof, and to provide, with the bearing 12, a two-point support for the drive shaft 11.

As a result of the bearing 12 being disposed within the chamber 3, said bearing normally would be subject to the heated atmosphere in the chamber 3. The bearing also would be difficult to lubricate under ordinary circumstances. In the above noted prior patents the long bonnet 15a is constructed in a manner to provide for efficient lubrication of the inner bearing 12 and to provide a cooling air at one side only of the bearing, and with the cooling air passing around the lubricating means for the bearing, for the purpose of keeping the bearing and the lubricant cool. In the present instance the long inner extended end or bonnet 15a of the drive unit is designed and constructed in such a manner that the cooling air passes completely around all sides of the inner bearing 12.

In the present instance the circulating passages for the cooling air are so arranged that the air is first drawn from outside the wall 2 of the

chamber 3. The air is delivered into an air circulating space disposed between the bearing 12 and the end wall of the hollow structure 15 lying adjacent the driven element 10. The air, after 5 being circulated about the inner side of the bearing 12, passes through passages disposed radially beyond the bearing 12. These passages deliver the air into the interior of the structure 15 around the outer end of the bearing 12. The air is then 10 discharged from the interior of the structure 15 to the atmosphere.

The above noted circulation is provided by a set of blades, fins or veins 30 formed on one side of a disc 28. The disc 28 constitutes the body 15 portion of an air circulating fan 25 and functions as a baffle or partition between the opposite ends of the hollow structure 15. The disc 28 extends radially from and circumferentially about a hub 29, which is secured to the drive shaft 11. The 20 blades 30 are so arranged on the disc 28 that, upon rotation of the shaft 11 in its normal direction, air is expelled from that portion of the interior of the hollow structure 15 lying at one side of the baffle or partition formed by the disc 28, 25 through a series of exhaust openings 26 which are formed in and spaced around the shell of the main body portion 15b of said structure.

The fan 25 consisting of the hub 29, the disc 28, and veins 30, is also provided with a second 30 set of blades or veins 27, on the side of the disc 28 opposite to that on which the blades or veins 30 are formed.

The blades or veins 27 are arranged to draw air, through suitable openings 22 formed in the 35 short bonnet 15a, into the portion of the main body 15b occupied by the motor stator and rotor 20 and 21 and to exhaust the air through the radial ports 26 above mentioned, said air passing between said rotor and stator and around the 40 windings thereof to keep the motor cool.

The air for cooling the inner bearing 12 enters the hollow structure 15 through a plurality of radial ports 31 which are formed in that portion of the bonnet 15a which lies between the supporting flange 16 and the main body portion 15b of the hollow structure 15, said ports, in the present instance, being disposed at substantially 45 90° apart circumferentially of said structure. Each of the ports 31 is connected by a duct 40 to an annular air space 41 which is formed in the bonnet 15a, intermediate the opposite ends thereof. The annular air chamber 41 is connected by ports 42, formed in a transversely extending wall 43 of said bonnet, with an inner 50 transversely extending air chamber 44. The air chamber 44 extends completely across the inner end of the bonnet 15a, between the wall 43 in which the bearing 12 is mounted and supported and the end closure plate 45 of the hollow structure 15 which is secured to the inner end of said 55 long bonnet, whereby air is circulated completely around the bearing 12 from the shaft 11 to the outer peripheral wall of the bonnet, between the bearing 12 and the closure plate 45. The air passes outwardly, i. e. axially of the shaft 11, 60 from the air chamber 44 into the interior of the hollow bonnet 15a and the body portion 15b of the structure 15, through a series of ports 46. The ports 46 are formed in and through the bearing supporting wall 43, between the outer series 65 of circumferentially extending ports 42 and the bearing 12. In this manner cooling air is circulated completely around all sides of the inner bearing 12. The bearing 12 is, in the present 70 instance, in the form of an anti-friction or ball- 75

bearing. The inner race 47 of the bearing 12 is mounted on the shaft 11 and the outer race 48 of said bearing is mounted in a cavity 49 formed in a central boss 50, which in turn is formed in the bearing supporting wall 43. The outer race 48 is secured in position, against excessive axial movement, by a cap 51 which is secured to the wall 43 by cap screws 52. The inner race 47 is secured to the shaft 11, against relatively axial movement, by a nut 53 which is threaded onto 10 said shaft. The nut 53 is disposed in a cavity 54 formed in the cap 51 and is provided with an annular flange 55 which projects into an annular groove 56 formed in the cap 51.

Lubricant is forced into the bearing cavity 49 11 through a radial passage 57, which is formed in the wall 43, and communicates with an intersecting passage 58, which is also formed in said wall. The passage 58 is connected by a tube 59 with a fitting 60 mounted on the outside of the bonnet 15a, between the supporting flange 16 and the body portion 15b of the structure 15. The lubricant tube 59, as clearly shown in Figs. 2 and 4, is located entirely within the space in the bonnet 15a through which the cooling air is constantly being circulated, whereby the lubricant is kept cool.

The boss 50, cap 51 and closure plate 45 are each provided with packing rings 61 by which the lubricant is prevented from escaping, and, in the case of the closure plate 45, the packing ring 61 prevents heated air from entering the cooling air chamber 44 from the drying chamber 3, in which the driven element 10 is mounted.

In that form of the invention shown in Figs. 34 to 4 inclusive, the two series of air passages 42 and 46 in the bearing supporting wall 43 are circumferentially arranged on arcs or circles of different radii with respect to the axis of the shaft 11, arranged concentrically with one series 40 radially outward with respect to the other series. In the modified form of the invention shown in Figs. 5 and 6 the corresponding series of passages 42a, 46a through the bearing supporting wall 43a are arranged circumferentially on the same 45 radius with respect to the axis of the shaft 11, with the passages 42a alternating with the passages 46a around said shaft.

Also in the modified form shown in Figs. 5 and 6 the annular air passage 41 is eliminated. In 50 this case, ducts 40a extend from the ports 31a to the wall 43a and communicate directly with the passage 42a in said wall. The structure shown in Figs. 1 to 4 however, is preferable in that the annular air passage 41 eliminates the radiation 55 of heat from the peripheral wall of that portion of the bonnet 15a which projects into the heated chamber 3 directly into the interior of the bonnet. The structure shown in Figs. 5 and 6 however, is applicable in cases where the temperature 60 within the chamber 3 are not extremely high.

As shown in Figs. 2 and 4, the circular wall 62, the inner end wall 63 of the annular passage 41 and that portion of the transverse wall 43 which lies between the circular wall 61 and the shaft 65 11, constitutes an end closure for the interior of the hollow structure 15. The outer shell of the bonnet end 15a of said hollow structure, together with the closure plate 45 forms an outer casing for said closure end of the hollow structure and 70 provides a complete air space or void composed of the spaces 41, 44 and openings 42 around the end of the structure which normally projects into the heated atmosphere of the drier. This air space 75 prevents heat from radiating from the outer shell

directly into the motor housing formed by the structure 15. The air circulated to and from and in the void between the inner and outer walls of the extended end of structure 15 continuously carries off any heat that radiates inwardly from the outer wall or shell.

I claim:

1. A motor comprising a rigid hollow structure, a single one piece shaft in and extending continuously from end to end of said structure, a bearing adjacent each end solely of said structure for supporting said shaft with one of said bearings disposed entirely within and completely enclosed by said structure and with voids completely surrounding said enclosed bearing longitudinally and transversely thereof, said voids being in communication with the atmosphere outside said structure through ingress and egress air passages remotely situated longitudinally of said structure with respect to said fully enclosed bearing, and means for passing air through said ingress and egress and said bearing-surrounding voids.

2. A motor comprising a rigid hollow structure including a transverse end wall, a second transverse wall within said structure adjacent and in spaced relation to said end wall and providing a void between said walls, a shaft in said hollow structure and having one end projecting through aligned openings in said walls respectively, said end wall being sealed against the ingress or egress of air to or from said void around said shaft, a bearing for supporting said end of said shaft in said second wall and terminating inwardly from said end wall, said bearing-supporting wall having openings extending therethrough and disposed radially beyond said bearing and communicating with the void between said spaced walls, air ducts connecting predetermined openings in said second wall with the atmosphere outside said structure at a predetermined distance inwardly along said structure from said end wall, and means for passing air through said ducts, said openings and said void around said bearing.

3. A motor comprising a rigid hollow structure including a transverse end wall, a second transverse wall within said structure adjacent and in spaced relation to said end wall and providing a void between said walls, a shaft in said hollow structure and having one end projecting through aligned openings in said walls respectively, said end wall being sealed against the ingress or egress of air to or from said void around said shaft, a bearing in said second wall for supporting said end of said shaft and terminating inwardly from said end wall, said bearing-supporting wall having openings extending therethrough and disposed radially beyond said bearing and communicating with the void between said spaced walls, air ducts connecting predetermined openings in said second wall with the atmosphere outside said structure at a predetermined distance inwardly along said structure from said end wall, the remainder of said openings affording communication between the interior of said hollow structure and the void between said transverse walls, said hollow structure having exhaust openings to the atmosphere outside said structure and disposed at a predetermined distance inwardly along said structure from said end wall, and means for passing air through said ducts, said openings and said void around said bearing.

4. A motor comprising a rigid hollow structure including a transverse end wall, a second transverse wall within said structure adjacent and in

spaced relation to said end wall and providing a void between said walls, a shaft in said hollow structure and having one end projecting through aligned openings in said walls respectively, a bearing in said second wall for supporting said end of said shaft and terminating inwardly from said end wall, said bearing-supporting wall having openings extending therethrough and disposed radially beyond said bearing and communicating with the void between said spaced walls, a circumferentially extending air chamber adjacent said second transverse wall and communicating with predetermined openings in said second wall, air ducts affording communication between said air chamber and the atmosphere outside said hollow structure, and means for passing air through said air ducts, said air chamber, said openings and said void around said bearing.

5. A motor comprising a rigid hollow structure including a transverse end wall, a second transverse wall within said structure adjacent and in spaced relation to said end wall and providing a void between said walls, a shaft in said hollow structure and having one end projecting through aligned openings in said walls respectively, a bearing in said second wall for supporting said end of said shaft and terminating inwardly from said end wall, said bearing-supporting wall having two concentric series of openings extending therethrough and disposed radially beyond said bearing and communicating with the void between said spaced walls, and means for passing air through one of said series of openings into said void and from said void into the second series of openings around said bearing.

6. A motor comprising a rigid hollow structure including a transverse end wall, a second transverse wall within said structure adjacent and in spaced relation to said end wall and providing a void between said walls, a shaft in said hollow structure and having one end projecting through aligned openings in said walls respectively, a bearing in said second wall for supporting said end of said shaft and terminating inwardly from said end wall, said bearing-supporting wall having two concentric series of openings extending therethrough and disposed radially beyond said bearing and communicating with the void between said spaced walls, air ducts affording communication between one of said series of openings and the atmosphere outside said structure, said structure having a series of openings affording communication between the second series of openings and the atmosphere outside said structure, and means for passing air through said air ducts and one of the said series of openings into said void and from said void into the second series of openings around said bearing and through the openings in said structure to the atmosphere outside said structure.

7. A motor comprising a rigid hollow structure including a rigid body portion and a relatively long end portion of correspondingly rigid construction projecting from said body portion, said end portion including a double relatively spaced walled structure extending substantially from said body portion to and across the outer remotely situated end of said end portion, a single one piece shaft in and extending continuously from end to end of said hollow structure with one end projecting through aligned openings in the double walled outer end of said end portion, and a bearing in the inner of the two walls of said outer remotely situated end of said end portion for solely supporting said end of said shaft.

8. A motor comprising a rigid hollow structure including a rigid body portion and a relatively long end portion of correspondingly rigid construction projecting from said body portion, said end portion including a double relatively spaced walled structure extending substantially from said body portion to and across the outer remotely situated end of said end portion, a single one piece shaft in and extending continuously from end to end of said hollow structure with one end projecting through aligned openings in the double walled outer end of said end portion, a bearing in the inner of the two walls of said outer remotely situated end of said end portion for solely supporting said end of said shaft, and means for circulating air in the void between said double walls of said end portion.
9. A motor comprising a rigid hollow structure including a rigid body portion and a relatively long end portion of correspondingly rigid construction projecting from said body portion, said end portion including a double relatively spaced walled structure extending substantially from said body portion to and across the outer remotely situated end of said end portion, a single one piece shaft in and extending continuously from end to end of said hollow structure with one end projecting through aligned openings in the double walled outer end of said end portion, a bearing in the inner of the two walls of said outer remotely situated end of said end portion for solely supporting said end of said shaft, and means for circulating air to and from and in the void between said double walls of said end portion.

HERMANN S. BOGATY.
